UNITED STATES PATENT OFFICE.

JAMES BELL FORTNAM, OF NEW YORK, N. Y.

GAME APPARATUS.

1,056,526.

Specification of Letters Patent.

Patented Mar. 18, 1913.

Application filed March 12, 1912. Serial No. 683,210.

To all whom it may concern:

Be it known that I, JAMES B. FORTNAM, a citizen of the United States, and a resident of the city of New York, borough of Brooklyn, in the county of Kings and State of New York, have invented a new and Improved Game Apparatus, of which the following is a full, clear, and exact description.

My invention relates to games, and it has 10 for its object to provide a new game apparatus with which may be played several interesting games, the game apparatus consisting of a board with a group of forty-one hexagonal spaces, there being a star in the 15 space in the center of the board, and marks to indicate the castles which are spaced apart at each side of the board. Around the group of the said spaces there are a plurality of markings, spaced apart, upon 20 which the players may each move their pieces, the play of which is confined to these markings around the group of the hexagonal spaces. These pieces, when located on certain of the markings limit the plays 25 which may be made by the opposing player on the group of the hexagonal spaces.

Additional objects of the invention will appear in the following complete specification in which the preferred form of the invention is disclosed.

In the drawings similar characters of reference indicate corresponding parts in all the views, in which—

Figure 1 is a plan view of the board; Fig. 2 is a view showing one of the pieces designated as "kings"; Fig. 3 is a view showing one of the pieces designated as "knights"; Fig. 4 is a view showing one of the pieces designated as "dukes"; and Fig. 5 is a view 40 showing one of the pieces designated as "block pieces".

By referring to the drawings it will be seen that the board 11 is marked with hexagonal spaces, the sides of which are parallel with adjacent hexagonal spaces. These hexagonal spaces, which are referred to on the drawings by the reference character 12, are disposed from the side 13 of the board to the side 14 of the board, and with sides 45 parallel with the said sides 13 and 14. The center column or path 15 extends from one side of the board to the other, and is formed by seven hexagonal spaces, and the paths 16, one at each side of the path 15 is formed by 50 six hexagonal spaces. The paths 17, one at each side of the paths 16 are formed by five

hexagonal spaces, and the paths 18, one at each side of the paths 17, are formed by six hexagonal spaces. The hexagonal spaces in the paths 15 and 17 are colored in contrast 60 to the hexagonal spaces forming the paths 18 and 16. The spaces 18^a and 18^b at the ends of the paths 18, and the spaces 15^a and 15^b at the ends of the path 15 are distinguished by characters, and are referred to 65 as castles, the spaces 15^a and 18^a having thereon the characters 19, and the spaces 15^b and 18^b having printed thereon the characters 20. The central space 21 in the path 15 has a star 22 printed thereon. Around the 70 board there are markings 23, 24, 25 and 26, which are spaced apart as will be seen by referring to Fig. 1 of the drawings. The markings 23 are of the same color as the hexagonal spaces in the paths 16, and 18, 75 while the markings 24 are of the same color as the hexagonal spaces in the paths 15 and 17. There are arrows 27 on the board, which indicate how the duke piece may be moved on the markings 23, 24, 25 and 26, 80 with certain results.

In Fig. 2 of the drawings I show one of the pieces designated as a king, and indicated by reference character 28.

In Fig. 3 I show one of the pieces designated as a knight, indicated by the reference character 29.

In Fig. 4 I show one of the pieces designated as a duke, and indicated by the reference character 30.

In Fig. 5 I show a block piece, and indicated by the reference character 31.

Several very interesting games may be played with my game apparatus, one of these games is a game which I designate as 95 the "hexagon game," which may be played by two players, the rules of which are as follows:

The game is played on a diagram of forty-one hexagonal spaces. Three spaces for 100 each side, designated by emblems which are called castles, surrounded by eight circular spaces.

Pieces.—Each side has ten pieces; one king, three knights and six block pieces.

105

Moves.

King move.—The king has two ways of moving—1st, position move; 2d, jumping move. 1st, position move is a move of one 110 space in any direction to an unoccupied space; 2d, jumping move is a move made

by jumping one or a number of allied or opponent's pieces, under the following restrictions. In jumping allied pieces, the king has the option of jumping one or several as he elects. In jumping opponent's pieces, which constitutes capture, the king is compelled to complete the full series of jumps, unless it is possible for him to branch off over allied pieces.

10 *Capturing.*—The king captures opponent's pieces by jumping. It is compulsory for the king to capture on direct jumps when possible if opponent so elects, unless an allied knight can make the capture by direct or indirect jumps. Direct means over opponent's pieces. Indirect means over allied pieces first. The king has the power of jumping any piece on the board.

20 *Knight's move.*—The knight moves are similar to the king moves, except that he cannot jump his allied king or knight, nor is it compulsory for him to jump or capture opponent's pieces. Be it understood that allied pieces remain on the board when 25 jumped.

25 *Block pieces.*—The block pieces move one space at a time in a forward direction to space at a time in a forward direction to unoccupied spaces. Forward direction 30 means any of the three hexagons in front of it. Block pieces cannot jump.

30 *Block pieces knighted.*—A block piece reaching any of the opponent's castles must be given the power of a knight starting from 35 that position.

35 *Winning the game.*—The game is won when the opponent's king is captured, or when the allied king reaches one of the opponent's castles.

40 *Set-ups.*—There are four set-ups possible in starting this game; one of these set-ups is by placing the king on the hexagonal space marked 5, knights on the spaces marked 4, 6 and 8, and block pieces on 45 spaces marked 1, 2, 3, 7, 9 and 10. Another set-up is by placing the king on the space 5, the knights on the spaces 3, 6 and 7, and the block pieces on spaces 1, 2, 4, 8, 9 and 10. Still another set-up is by placing the king 50 on the space 5, the knight pieces on the spaces 1, 6 and 9, and the block pieces on the spaces 2, 3, 4, 7, 8 and 10. Still another set-up is by placing the king on the space 5, the knights on the spaces 2, 6 and 10, and the block pieces on the spaces 1, 3, 4, 7, 8 and 55 9.

60 The player having chosen one of the set-ups starts by moving any piece one space, or jumping one of his knights over one or more allied pieces, black starting first. It is better to choose one particular set-up till familiar with the game, after which black chooses first and white may oppose with any of the four. The game may also 65 be played with the outside move, called

the duke move, for which see hexagon chess, the rules for this particular part being the same.

65 *Odds.*—If one party is a superior player he may give the odds of a duke, a knight, or 70 block piece to make up the deficiency.

75 Another interesting game is the game of hexagon chess, the rules for playing which are as follows, diagram same as for hexagon:

80 *Pieces.*—Each side has eleven pieces; one king, three knights, six block pieces, and the outside piece, called the duke.

Moves.

85 *King moves.*—The king has two ways of moving—1st, position move; 2d, jumping move. 1st, position move, is a move one space in any direction to an unoccupied space. 2d, jumping move, is made by jumping one or a number of opponent's pieces in any direction which constitutes capture. It is not compulsory for the king to jump and when doing so may jump as many or as few 90 as he elects.

90 *Knight's move.*—The knights move in any direction and as far as the player desires, provided they move only in a straight line. They may not pass over a piece but may capture an opposing piece by moving into 95 the space occupied by that piece, thus removing him from the board. The knight may capture only one man at a time.

95 *Block pieces.*—The block pieces can be moved one space at a time in a forward direction to unoccupied spaces. Forward direction means any of the three hexagonal spaces in front of it. They may capture any 100 opposing piece or pieces in their path by jumping, provided there is a vacant space 105 beyond each piece captured. Any of these pieces reaching opponent's emblems must be given the power of a knight, starting from that space. The space bearing the star does not enter into hexagon chess, and none of the 110 pieces can move on or over it. Block pieces must capture when possible.

110 *Moves of the dukes.*—The duke pieces are placed on the markings of the circular spaces 115 26. They may move to the adjacent circle at the right or left at each turn to move. Dukes capture when adjacent, and when moving in the direction of the arrows. It is compulsory to capture when possible. Not more than one circuit of the board can be 120 made by the duke pieces before moving some other piece. When the duke piece occupies an opponent's circular space it prevents moves by opponent's king and block pieces 125 occupying similar colored spaces. This rule does not affect the knight pieces.

125 *Winning the game.*—The game is won when the opponent's king is captured.

130 The set-ups are the same as for the hexagon game.

Opening the game.—Black starts first by moving king, knight, block pieces or duke. White follows.

Still another interesting game which may be played with my game apparatus is the game entitled "giant's castle," the rules for playing which are as follows:

Number of players.—The game may be played by five, three, or two persons.

10 *Five players.*—Pieces: One player takes a king piece. The other four players take each any three similar pieces called blocks.

Block moves.—Each of the four block players begin in turn by placing a block on any one of the six emblems. The second and succeeding moves may consist in moving his block that is on the board (if any) or starting another block on an emblem. The block piece can move only one space in any direction to another unoccupied space. The block pieces cannot capture except when reaching the start space if the king piece occupies it.

25 *King moves.*—The king moves from the star space any number of spaces in the direction indicated by the pointers on the start, then turns, and moves as before. The king must stop at a space occupied by a block, capture and remove him before proceeding further.

30 *Winning.*—The king wins when he captures all the block pieces. A block piece reaching the star space wins.

35 *Three players.*—When three persons play, one takes the king, the other two divide the twelve block pieces equally, using each one kind to distinguish the players. Two separate block pieces are played at each turn by each player.

40 *Two players.*—When two persons play, one takes the king, the other the twelve block pieces, playing three separate ones at each turn.

45 A fourth game, entitled "hop toad," may be played with my game apparatus, and following are the rules for the playing of this game: This game is one that will be readily understood by the children. The starting position, for this game is arranged by placing the block pieces on the spaces 1, 3, 15^a, 5, 7 and 9. The opposing side is arranged in the same position. The object of the game is to place one of your men on one of the opponent's three emblems or vice versa. Each party can move one piece at a time in 55 any of the three forward directions. They can also jump any of their own men or any of their opponent's men, but when jumping their opponent's men they remove them from the board. In jumping their own pieces, 60 said pieces remain on the board. They cannot move backward, but may jump back over their own pieces if in a position to do so. The men can jump in any direction over their own pieces or opponent's pieces, and 65 as many as they like. The center space bear-

ing the star cannot be occupied by any piece, nor can a piece be taken that would cause a piece to land on that space, but this space may be jumped and treated as though a permanent piece were stationed there.

70 *Winning the game.*—The game is won when a piece gains an opponent's emblem.

Having thus described my invention, I claim as new and desire to secure by Letters Patent:

75 1. In a game apparatus, a board having a plurality of hexagonal spaces, the spaces in each path from one player's side of the board to the other player's side being colored in contrast with the spaces in adjacent paths 80 extending in the same direction.

85 2. In a game apparatus a board having a path of seven hexagonal spaces, extending from one side of the board to the other, and with sides parallel with the said sides of the board, a path of six hexagonal spaces at each side of the first-mentioned path, with sides parallel with the sides of the first-mentioned spaces, a path of five hexagonal spaces at the outer side of each of the second-mentioned hexagonal spaces, and with sides parallel with the sides of the third-mentioned hexagonal spaces, and with sides parallel with the sides of the 90 third-mentioned hexagonal spaces.

95 3. In a game apparatus a board having a path of seven hexagonal spaces extending from one side of the board to the other, and with sides parallel with the said sides of the board, a path of six hexagonal spaces at each side of the first-mentioned path, with sides parallel with the sides of the first-mentioned spaces, a path of five hexagonal spaces at the outer side of each of the second-mentioned hexagonal spaces, and with sides parallel with the sides of the second-mentioned hexagonal spaces, a path of six hexagonal spaces at the outer side 100 of each of the third-mentioned hexagonal spaces, and with sides parallel with the sides of the third-mentioned hexagonal spaces, the first and third-mentioned paths of hexagonal spaces being colored in contrast with 105 the other spaces.

110 4. In a game apparatus a board having a path of seven hexagonal spaces, extending from one side of the board to the other, and with sides parallel with the said sides of the board, a path of six hexagonal spaces at each side of the first-mentioned path, with sides parallel with the sides of the first-mentioned spaces, a path of five hexagonal spaces at the outer side of each of the second-mentioned hexagonal spaces, and with sides parallel with the sides of the second-mentioned hexagonal spaces, and a path of six hexagonal spaces at the outer 115 side of each of the third-mentioned hex-

agonal spaces, and with sides parallel with the sides of the third-mentioned hexagonal spaces, the end spaces in the first and in the fourth paths being marked in contrast with 5 the other spaces.

5. In a game apparatus a board having a path of seven hexagonal spaces, extending from one side of the board to the other, and with sides parallel with the said sides of 10 the board, a path of six hexagonal spaces at each side of the first-mentioned path, with sides parallel with the sides of the first-mentioned spaces, a path of five hexagonal spaces at the outer side of each of 15 the second-mentioned hexagonal spaces, and with sides parallel with the sides of the second mentioned hexagonal spaces, and a path of six hexagonal spaces at the outer side of each of the third-mentioned hexagonal 20 spaces, and with sides parallel with the sides of the third-mentioned hexagonal spaces, the end spaces in the first and in the fourth paths being marked in contrast with the other spaces, the center space being 25 marked in contrast with the other spaces.

6. In a game apparatus a board having a group of spaces on which pieces may be played, and markings spaced apart around the said group on which an additional piece 30 may be played, and an arrow indicating the direction of certain plays for the last-mentioned piece.

7. In a game apparatus, a board having a path composed of a plurality of hexagonal spaces extending from one side of the board to the opposite side, and with sides parallel with the said sides of the board, a path of hexagonal spaces at each side of the first-mentioned path, and with sides parallel with 35 the sides of the first mentioned path, the said spaces in each of the second-mentioned paths being one less in number than the spaces of the first path, a path of hexagonal spaces at the outer side of each of the second-mentioned hexagonal spaces, and with 40 sides parallel with the sides of the second-mentioned hexagonal spaces, the hexagonal spaces in each of the third-mentioned paths being one less in number than the hexagonal 45 spaces in the second-mentioned paths, a path of hexagonal spaces at the outer side of each of the third-mentioned hexagonal spaces, and with sides parallel with the sides of the third-mentioned hexagonal 50 spaces in the second-mentioned paths, a path of hexagonal spaces at the outer side of each of the third-mentioned hexagonal spaces, and with sides parallel with the sides of the third-mentioned hexagonal

spaces, the hexagonal spaces in the fourth- 55 mentioned path being one more in number than the hexagonal spaces in the third-mentioned path.

8. In a game apparatus a board having a path of seven hexagonal spaces, extending 60 from one side of the board to the other, and with sides parallel with the said sides of the board, a path of six hexagonal spaces at each side of the first-mentioned path, with sides parallel with the sides of the 65 first-mentioned spaces, a path of five hexagonal spaces at the outer side of each of the second-mentioned hexagonal spaces, and with sides parallel with the sides of the second-mentioned hexagonal spaces, and a path 70 of six hexagonal spaces at the outer side of each of the third-mentioned hexagonal spaces, and with sides parallel with the sides of the third-mentioned hexagonal spaces, markings spaced apart, around the hexagonal 75 spaces on which a piece may be played, and an arrow indicating the direction of certain plays.

9. In a game apparatus a board having a path of seven hexagonal spaces extending 80 from one side of the board to the other, and with sides parallel with the said sides of the board, a path of six hexagonal spaces at each side of the first-mentioned path, with sides parallel with the sides of the first- 85 mentioned spaces, a path of five hexagonal spaces at the outer side of each of the second-mentioned hexagonal spaces, and with sides parallel with the sides of the second-mentioned hexagonal spaces, a path of six hexagonal 90 spaces at the outer side of each of the third-mentioned hexagonal spaces, and with sides parallel with the sides of the third-mentioned hexagonal spaces, the first and third mentioned paths of hexagonal 95 spaces being colored in contrast with the other spaces, and markings spaced apart around the hexagonal spaces in each of said colors.

In testimony whereof I have signed my 100 name to this specification in the presence of two subscribing witnesses.
